(57) **CLAIM**

The ornamental design for a socket power supply housing, as shown and described.

DESCRIPTION

FIG. 1 is a perspective view of a socket power supply housing showing my new design.

FIG. 2 is a rear view thereof.

FIG. 3 is a front view thereof.

FIG. 4 is a right end view thereof.

FIG. 5 is a left end thereof.

FIG. 6 is a top view thereof; and,

FIG. 7 is a bottom view thereof.

The broken lines shown are for illustrative purposes and form no part of the claimed design.

The views shown broken away are to represent indeterminate length.
